CLAIM

The ornamental design for a purse, as shown and described.

DESCRIPTION

FIG. 1 is a plan view of the outside of a purse showing my new design;

FIG. 2 is a right side elevational view thereof;

FIG. 3 is a rear elevational view thereof;

FIG. 4 is a plan view of the inside thereof;

FIG. 5 is a front elevational view thereof;

FIG. 6 is an inside right perspective view thereof showing the purse partially open;

FIG. 7 is an outside right perspective view thereof showing the purse completely closed; and,

FIG. 8 is an inside front left perspective view showing the purse fully open and showing a coin compartment thereof. The left side elevational view is a mirror image of the right side elevational view shown in FIG. 2.
